United States Patent Office

Des. 234,124
Patented Jan. 21, 1975

234,124

CLOCK

Joseph E. F. Goddard, 144 Warren Ave.,
East Providence, R.I. 02914

Filed Nov. 24, 1972, Ser. No. 309,103

Term of patent 14 years

Int. Cl. D10—01

U.S. Cl. D10—9

FIG. 4

FIG. 5

FIG. 1 is a front elevation of my new design for a real or simulated coconut clock housing;

FIG. 2 is a side elevational view thereof taken from the right side of FIG. 1;

FIG. 3 is a top plan view thereof;

FIG. 4 is a rear elevation view of FIG. 1;

FIG. 5 is a bottom plan view of FIG. 1.

I claim:

The ornamental design for a clock, as shown and described.
